(57) **CLAIM**

The ornamental design for a blanket with pocket, as shown
and described.

DESCRIPTION

FIG. 1 is a front, right side perspective view showing my new
design of the blanket with pocket design;

FIG. 2 is a top side view thereof;

FIG. 3 is a bottom side view thereof;

FIG. 4 is a right side elevational view thereof;

FIG. 5 is a left side elevational view thereof;

FIG. 6 is a rear elevational view thereof; and,

FIG. 7 is a front elevational view thereof.

The broken lines showing an optional folded blanket or pillow
within the pocket are for environmental purposes only and
form no part of the claimed design.
